Howam v Howam

UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A COMBINATION TYPE-BORDER.

SPECIFICATION forming part of Design No. 19,659, dated February 18, 1890.

Application filed January 27, 1890. Serial No. 338,292. Term of patent 7 years.

To all whom it may concern:

Be it known that I, HERMAN IHLENBURG, a citizen of the United States, and a resident of Philadelphia, Pennsylvania, have invented a Design for a Combination-Border Type, of which the following is a specification.

My design is clearly shown in the accompanying typographic impression, to which reference is made.

10 The general feature of the design is the representation of a covering paper or card torn and turned back so as to expose the surface beneath.

15 The font in the present instance comprises fifty-one (51) characters. All the characters, with the exception of Nos. 3, 4, 5, 6, 42, and 48, represent irregularly-torn portions of the covering-sheet, the characters 42 and 48 representing the covering-sheet rolled at the 20 corner in the form of a scroll, so as to expose an under surface. The characters 3 and 6 are zigzag-line work, while the characters 4 and 5 represent cross-bar work, these char-

acters forming the groundwork of some of the others. The characters above alluded to 25 may be combined in many different forms, a representation of the combination of characters being shown beneath the representations of the separate characters.

This combination-border type may be used 30 in connection with the letter-type which is clearly shown and described in my application for design patent filed of even date here-with.

I claim—

35 The design for the combination-border type, substantially as herein shown and described.

In testimony whereof I have signed my name to this specification in the presence of two subscribing witnesses.

HERMAN IHLENBURG.

Witnesses:

C. F. HUCH,
HERMAN METIUS.
